UNITED STATES PATENT OFFICE.

JULES D'HARVENG, OF LIEGE, BELGIUM.

TWO-CYCLE EXPLOSION-MOTOR.

1,081,492.

Specification of Letters Patent. Patented Dec. 16, 1913.

Application filed April 1, 1911. Serial No. 618,415.

To all whom it may concern:

Be it known that I, JULES D'HARVENG, a subject of the Kingdom of Belgium, residing in Liege, Belgium, have invented certain new and useful Improvements in Two-Cycle Explosion-Motors; and I do hereby declare the following to be a full, clear, and exact description of the invention, such as will enable others skilled in the art to which it appertains to make and use the same, reference being had to the accompanying drawings, and to letters or figures of reference marked therein, which form a part of this specification.

15 The present invention has for its object an injector for liquid fuel for explosion motors in which the liquid fuel is introduced into the working cylinder by injection into the combustion air in proximity to the inlet to the working cylinder, this injection being regulated in such a manner that during the period of admission counting from the commencement of the injection of the fuel, the supply of combustion air and the supply of liquid fuel are in fixed proportion under all conditions of running.

By means of this device an explosive mixture is introduced which is nearly in condition for use at the inlet to the cylinder, and 30 the mixture has only to be completed in the working cylinder, which itself constitutes the mixing chamber of the carburetor.

In order to obtain this result in accordance with this invention the property presented 35 by resilient diaphragms or disks, of generating in their resilient deformation a volume proportionate to the specific pressure that they experience, is utilized.

The accompanying drawings represent the 40 various elements of this injector and its application to a two-cycle motor.

Figure 1 is a section of a two-cycle, single cylinder motor with two reservoirs, showing an application of the injector. Fig. 2 is a 45 diagram corresponding to the application illustrated in Fig. 1, of the pressures in the charging reservoir and upon the driving face (dry) of the resilient disk of the pulsator. Fig. 3 is a section of a two-cycle, two- 50 cylinder motor with one reservoir per cylinder

only, showing another application of the injector. Fig. 4 is a section of a resilient disk pulsator (on the line A—B in Fig. 5) which pulsator together with the jet or jets that it supplies, constitutes the injector. Fig. 5 is a section of the pulsator on the lines C D E F in Fig. 4. Fig. 6 is a diagram (corresponding to the application shown in Fig. 3) of the pressures in the reservoir of one of the cylinders and upon the driving 6 face (dry) of the disk of the corresponding pulsator. Fig. 7 is a similar diagram in the case in which the motor in Fig. 3 is provided with a separate scavenging air reservoir (as in the case illustrated in Fig. 1).

This injector consists essentially—1. Of a resilient disk pulsator (Figs. 4 and 5) one of the faces of which (the wet face) in contact with the liquid fuel contained in the chamber 28 communicates with the suction pipe 20 and delivery pipe 24 for the fuel, each of which is provided with its own valve, of any suitable construction, for example the non-return valves 21 and 23 respectively, while the other face (the dry face) is subjected to a substantially constant pressure of any desired value, by suitable means, during the entire period of injection. 2. Of one or more jets connected with the delivery pipe of the pulsator. The jet is arranged in proximity to the inlet to the working cylinder and is directed in such a manner that the stream of liquid is discharged through the orifice toward the cylinder.

As indicated in the accompanying drawing a single pulsator can supply several jets but this arrangement can only be adopted for motors which run at a relatively low speed.

For high speed motors and motors for locomotion purposes in particular it is generally preferable to employ a single jet per pulsator and to unite these two parts of the injector into a single part presenting as its delivery conduit only the jet itself which should be as short as possible in such a manner as to reduce to the minimum the effects of inertia of the liquid column during the operation of the jet.

It should be noted that it will generally

be preferable to arrange the suction valve as close as possible to the disk. It is also generally advisable to locate a delivery valve at the extremity of the jet and in this case 5 it is possible to dispense with the delivery valve of the pulsator as the jet valve will fulfil the same purpose. The chief advantage to be obtained from this latter arrangement is greater certainty in avoiding any 10 accidental escape of the fuel either owing to the inclination of the machine during locomotion or by the action of the scavenging air in the case of two-cycle motors with a single reservoir or for any other reason. 15 The application of the injector to two-cycle motors is effected as follows: The dry face of the disk of the pulsator is subjected during the operation of the jet to a pressure which is substantially constant and at 20 least equal to the instantaneous pressure prevailing in the charging reservoir at the commencement of the introduction of the combustion air and the point of the jet is located in the charging reservoir in proximity to the orifice. In this manner that 25 which produces the injection is the drop in pressure in the reservoir and as the falls of pressure in the reservoir are proportionate to the quantities of air discharged therefrom 30 through the orifices and as the volumes of fuel supplied by the disk of the pulsator vary with the fall in pressure counting from the time the fuel injection commences it follows that, neglecting the quantity of 35 air which has entered the cylinder when the fuel injection commences, the quantity of air and fuel afterward admitted will be in fixed proportion. In order to obtain this result, it is therefore only necessary that 40 the constant pressure applied to the dry face of the disk shall balance the pressure prevailing in the reservoir when the latter contains only combustion air this pressure being assisted by all the static charges applied to the injection conduit such as the 45 pressure of the delivery valve, the pressure due to the difference of level between the disk and the point of the jet and so forth.

If the motor comprises two reservoirs, 50 one for the combustion air and one for the scavenging air as in the embodiment illustrated in Fig. 1, which is taken by way of example it is the pressure of the charging reservoir which together with the static resistances of the injection conduit that has 55 to be balanced by the pressure established in the dry chamber of the pulsator.

In Fig. 1, the piston 1 carries a cylindrical extension 2 acting as a valve and whose 60 upper end slides between the cylinder 3 and the re-entrant head 4. The chamber 5 between the head and cylinder in which the upper end of the valve 2 slides can be used as a lubricating chamber. The spark plug

6 is located in the head 4. In the dead center position of crank shaft 27 as shown, the ports 8 in the valve register with admission ports in the cylinder and the ports 7 in the valve with the exhaust ports 9. The ports 8 control ports 10 and 11 of two annular reservoirs 12 and 13 supplied by compressed air by a suitable pump. In Fig. 1, the pump piston is formed by the enlarged lower end of the piston 1. The air is drawn through valve 14 into the pump chamber 15 and is forced through valve 16 into reservoir 12 and also through valve 17 into reservoir 13. The jet or jets 18 inject the fuel.

The motor operates in the following manner: The piston being at the top of its stroke the various ports are closed and a mixture of air and fuel is compressed between the said piston and the cylinder head; this mixture is ignited by the sparking plug 6 and the piston effects its working stroke. The said mixture expands until ports 7 uncover the exhaust ports 9. Slightly afterward the lower edges of the ports 8 uncover the ports 11 of the reservoir 13 containing air under pressure. This air rushes into the cylinder and scavenges it and an instant after the lower edges of the ports 8 uncover the ports 10 of the reservoir 12; the combustion air contained in this reservoir 12 enters the cylinder with the fuel supplied by the jet or jets. The piston then rises and closes all the ports that have previously been opened and compresses the explosive mixture.

In order to inject fuel into the current 1 of air leaving the reservoir 12 while the said reservoir is in communication with the cylinder a distributor is utilized, Figs. 4 and 5. This distributor comprises an elastic diaphragm 22, one face of which (the right hand face Fig. 5) is displaced in a pressure chamber 19 in which at the proper moment the necessary variations of pressure are produced. This diaphragm acting as a pump piston sucks the liquid fuel supplied through the pipe 20 and the suction valve 21 by its other face (the left hand face) and forces it into the nozzle or nozzles 18 through the delivery valve 23 and a pipe 24. The valve 23 is held seated by 11 a spring 35 whose tension is adjusted by screw 36 and the diaphragm is limited in its movement in the pressure chamber by stops 29.

The necessary variations of pressure in 12 the chamber 19 of the distributor are obtained by placing this chamber 19 in communication at the proper moment either with the outer air through short pipe 37, or with the air reservoir 13 by means of a 12 pipe 25. For this purpose a distributing member 26 controlled by the driving shaft 27 is interposed on the pipe 25.

If the motor is a single reservoir motor as illustrated in Fig. 3 which is given by way of example it is the pressure obtaining in the reservoir after the departure of the scavenging air which along with the static resistances of the injection conduit has to be balanced by the pressure established in the dry chamber of the pulsator.

In the structure shown in Fig. 3, the 10 tons are 180° apart so that the reservoir 31² of the right hand cylinder for example is completely charged at the moment at which the operation of the jets 18' of the left hand cylinder should commence and remains 15 charged throughout this operation so that there will be available in this right hand reservoir 31² the correct constant pressure for operating the left hand jet or jets 18' during this admission. It will therefore be 20 sufficient in order to produce the distribution of the fuel to connect the chamber 19 of the left hand cylinder by means of a pipe 33 with the reservoir 31² of the right hand cylinder, and to connect the similar chamber 25 on the right hand side by a like pipe 33 with the left hand chamber 31', the chamber 31' being fully charged when the jets 18² for the right hand cylinder come into action.

The constant pressure that has to be applied to the disk of the pulsator is obviously necessary during the injection only; as it is necessary, after the operation of the jet, that the dry chamber pressure of the pulsator should be again brought to atmospheric pressure or to the pressure obtaining in the reservoir after the charging of the cylinder to permit a fresh quantity of fuel to enter the pulsator.

It is obvious that the constant pressure to be applied to the disk might be obtained by a special auxiliary pump but as in the case of two-cycle motors where a charging pump is already utilized, the air compressed by this pump can be employed for operating the pulsator and this so much the more so because it is not necessary that the pressure applied to the dry face of the disk should be greater than the charging pressure of the reservoir.

50 Taking by way of example the application of the injector to the motor shown in Fig. 1: In this case the dry face 19 of the pulsator is placed in communication at the proper moment through a conduit 25 either 55 with the external air or with the charging reservoir 13. With this object a distributor 26 is interposed on this tube 25 and operated from the driving shaft 27. With a suitable construction and adjustment of the distributor 26 the necessary pressures for producing the operation of the injector as described can be produced in the dry chamber of the pulsator. These pressures are indicated in broken lines in the diagram Fig. 2,

while the curve in firm lines represents the 65 pressure in the reservoir 12 which is charged at the same pressure as the reservoir 13.

The introduction of the mixture into the motor cylinder is effected from *e* to *a* and the diagram shows theoretically the corresponding fall of pressure in the reservoir 70

Prior to this fall of pressure from *d* to *g*, however, the dry chamber of the pulsator has been placed by the distributor 26 and the conduits 30 and 25 in communication with 75 the charging reservoir. At *d* it has been closed and it is the small charge thus imprisoned from *d* to *a* that has maintained the requisite pressure upon the dry face of the disk during the injection. Then at *a* the distributor has placed the dry chamber 19 of the pulsator in communication with the atmosphere through the pipes 25 and orifice 37. The dry chamber is closed by the distributor 26 from *b* to *c* and finally at *e* communication is again established with the reservoir and so on in succession. In this arrangement as the pressure in the dry chamber of the disk is equal to the pressure existing in the charging reservoir at the commencement of the introduction of the combustion air it is obvious that all the static losses of charge intervening in the delivery conduit of the pulsator and the jet must be reduced to the most favorable values. It 85 should also be noted that owing to the slight displacement of the resilient disk and to the relatively considerable dimensions of the reservoir 19 the expansion curve *c a* (Fig. 2) is in practice substantially a parallel with 90 the axis of the abscisse and that practically it may be taken that the pressure in the chamber 19 is constant during the injection.

In Fig. 1, in order to render the drawing clearer the conduits 24, 25 and 30 have purposely been shown of exaggerated length. In reality they are very short or even of no length. The distributor 26 and its operating means have been drawn solely with a view to ready comprehension.

The arrangement described above is applicable to all two-cycle motors but when the motor comprises a plurality of cylinders the arrangement can be still further simplified because if the cranks of the driving pistons of two cylinders are set at suitable angles we obtain in the reservoir of one of the cylinders for the benefit of the other the succession of pressures that were obtained above by the employment of the distributor 26. For this reason the cranks should be keyed at such an angle (Fig. 3) that the reservoir 31² of the right hand cylinder for example is fully charged at the moment at which the admission to the left hand cylinder should commence and remain charged during the whole of this admission. It is then only necessary to connect the dry chamber

ber of the pulsator with the charging reservoir of the twin cylinder (as represented diagrammatically in Fig. 5) of the two cylinder motor, the cranks of which are keyed 5 at an angle of 180° . If this motor comprises a single reservoir per cylinder the diagram of pressures is that shown in Fig. 6. $j g m k l$ is the line of fall of pressure, in the course of the fuel admission, in the reservoir 10 of the cylinder to be supplied with fuel, that is under consideration. $f h k' i$ is the line of pressures during the same period of time in the reservoir of the twin cylinder and consequently in the dry chamber of the 15 pulsator.

At any period of the admission determined for example by the line $k k'$ the ordinate $k' k''$ represents the total static pressure due to the static resistances of the delivery column resulting mainly from the tension of the spring of the delivery valve. $k'' k'''$ represents the value of the loss of pressure due to the dynamic resistances of the delivery column inertia and friction. 20 It is this value that should be reduced to the minimum. Finally $k''' k$ is the portion of the pressure balanced by the resilient tension of the deformed disk which has injected the corresponding volume of fuel. 25 It is this value that should be reduced to the minimum. Finally $k''' k$ is the portion of the pressure balanced by the resilient tension of the deformed disk which has injected the corresponding volume of fuel. 30 The injection therefore commences at m after the admission of the scavenging air that has caused the fall of pressure $k' k''$ and it continues to l the point of closing the orifices where the pressure ceases to decrease in the 35 reservoir. If the motor comprises two reservoirs the introduction of the scavenging air is independent of that of the mixing air and the succession of the pressures takes place as in Fig. 7. Here the value of the 40 loss of static charge due to the forcing column $P' P''$ is reduced to the minimum and in this manner the pressure $P' P'''$ corresponding to the utilizable maximum of the difference of pressure between $P' P'$ and P'' . 45 P''' is thus utilized for the resilient deformation of the disk and consequently for the injection.

It should be noted that the two-cylinder motor with cranks set at an angle of 180° 50 that has been taken by way of example presents a slight anomaly at the commencement of the introduction. This anomaly resides in the fact that, as shown in the diagram (Fig. 6) the maximum motor pressure acting upon the dry face of the disk is not yet quite reached at the point J which corresponds to the opening of the orifices but this anomaly is so small that it need not be taken into consideration and it will thus be seen 55 that the system is thoroughly applicable to multi-cylinder motors, the cranks of which are set at an angle of 180° .

As previously stated with reference to Fig. 1 the pipes affecting the injector are

merely shown diagrammatically for the sake 6 of clearness.

From what has been stated above it will be understood that the operation of the injector if this injector and the motor are adapted for the maximum speed that the 7 motor is able to attain is dependent directly and solely upon the introduction of the air no matter in accordance with what law this introduction takes place. The operation of the injector is therefore independent of the 7: velocity of the engine, that is to say, at all speeds the injector will introduce the same quantity of fuel in accordance with the law of proportionality enunciated.

The reduction of the motor couple and of 80 the speed is obtained merely by reducing the quantity of air admitted to the charging reservoir or reservoirs.

The essential advantages of the system applied to the two-cycle motors may be 85 summed up as follows: At each moment of the introduction of the mixture, whatever the conditions of running may be, the fuel delivered is proportionate to the total weight of the combustion air introduced into the 90 cylinder, (i. e., neglecting the quantity of air which has entered the cylinder when the fuel injection commences,) in such a manner as to obtain an explosive mixture of constant composition. This advantage results 95 from the resilient properties of the disk and the conditions in which it is placed.

I am aware that it has previously been proposed, in internal combustion engines, to employ resilient disks actuated by the pressure of the air to be supplied to the cylinder for feeding the liquid fuel, and I do not claim their use *per se*.

I claim—

1. The combination with an explosion engine having a charging reservoir; of a casing, an elastic diaphragm in the casing, a fuel inlet and a fuel discharge in the casing on one side of the diaphragm, communicating means between the casing and reservoir 10 on the other side of the diaphragm, and means to apply and release the pressure of said reservoir periodically on said other side of the diaphragm.

2. The combination with an explosion engine having a charging reservoir; of a casing, an elastic disk in the casing, a fuel inlet and a fuel outlet in the casing on one side of the disk communicating means between the casing on the other side of the 11 disk and the reservoir, and a valve to control the application and release of reservoir pressure on said other side of the diaphragm.

3. The combination with a plural cylinder explosion engine each cylinder having a 12 charging reservoir, and piston-controlled ports between reservoir and cylinder; of a fuel injector for each cylinder comprising

a casing, a diaphragm therein, a valve-controlled fuel inlet and valve-controlled fuel outlet for said casing on one side of the diaphragm and means to connect a casing of
5 one cylinder on the other side of its diaphragm with the reservoir of another cylinder.

In testimony that I claim the foregoing as my invention, I have signed my name in presence of two subscribing witnesses.

JULES D'HARVENG.
